United States Patent Office.

ALBERT D. JUDD, OF NEW HAVEN, CONNECTICUT.

Design No. 4,016, dated May 10, 1870.

DESIGN FOR A DRAWER-PULL.

The Schedule referred to in these Letters Patent and making part of the same.

To all whom it may concern:

Be it known that I, ALBERT D. JUDD, of New Haven, in the county of New Haven and State of Connecticut, have invented a new Design for Drawer-Pull; and I do hereby declare the following, when taken in connection with the accompanying drawings and the letters of reference marked thereon, to be a full, clear, and exact description of the same, and which said drawings constitute part of this specification, and represent in—

Figure 1, a front view; and in
Figure 2, a central section.

This invention relates to a design for the article of manufacture known to the trade as "drawer-pulls;" that is to say, a shell-form to be secured to the front of the drawer, by means of which the drawer may be opened.

The design consists in the peculiar form of the shell, whereby a better hold is given for the fingers.

The upper part of the shell A is of similar shape as other drawer-pulls, but the lower edge I contract or draw in, so that the upper part projects over the lower, as seen in fig. 2, thus affording a hold for the fingers. This peculiar shape is my design, and it may be ornamented in any desirable style.

I claim as my invention—

The design for drawer-pull, as herein described and shown.

A. D. JUDD.
